(57) **CLAIM**

The ornamental design for the portion of a container, as shown and described.

DESCRIPTION

FIG. 1 is a perspective view of the portion of a container of the present design.

FIG. 2 is a front elevation view of the portion of a container of FIG. 1, the opposite rear side elevation view being a mirror image.

FIG. 3 is a side elevation view of the portion of a container of FIG. 1, the opposite side elevation view being a mirror image.

FIG. 4 is a top plan view of the portion of a container of FIG. 1.

FIG. 5 is a bottom plan view of the portion of a container of FIG. 1; and,

FIG. 6 is an enlarged portion of the side elevation in cross section of the portion of a container of FIG. 1.

The broken line showing of a container is for illustrative purposes only and forms no part of the claimed design.
